UNITED STATES PATENT OFFICE

GROVER C. KIDWELL, OF MADISON, INDIANA, ASSIGNOR TO SCOTT-KIDWELL JACKET CO., OF MADISON, INDIANA, A FIRM

STUFFING MACHINE

Application filed June 19, 1928. Serial No. 236,627.

This invention relates to a stuffing machine and more particularly to a machine for stuffing cork in tubular fabric containers.

An important object of the invention is to provide a construction eliminating packing of the cork and permitting the use of a continuously reciprocating packer in the packing operation.

A further object of the invention is to provide a construction such that cork may be fed through feed tubes in which the packers reciprocate without interference by the packers.

A still further object of the invention is to provide a novel and improved means for controlling the feed of the cork to the feed tubes.

A still further object of the invention is to provide automatic means for determining the pressure at which the cork is packed in the containers.

A further and more specific object of the invention is to provide an apparatus for packing cork in the wall pockets of containers similar to that shown in my prior Patent, No. 1,587,655, granted June 8, 1926, for shipping jackets for ice cream containers.

These and other objects I attain by the construction shown in the accompanying drawings, wherein for the purpose of illustration is shown a preferred embodiment of my invention and wherein:

Figure 1 is a side elevation of a stuffing machine constructed in accordance with my invention;

Figure 2 is a view at right angles to the view of Figure 1;

Figure 3 is a section on the line 3-3 of Figure 1;

Figure 4 is a section on the line 4-4 of Figure 3;

Figure 5 is a section on the line 5-5 of Figure 2;

Figure 6 is a detail of the cam control mechanism;

Figure 7 is an enlarged detail sectional view on the line 7-7 of Figure 1.

Referring now more particularly to the drawings, the numeral 10 generally designates a suitable base having arising therefrom standards 11 arranged upon the four corners

of a rectangle. The upper ends of these standards are connected to one another by horizontal braces 12 and upon two of these braces are arranged bearings 13 for a drive shaft 14 having a centrally disposed crank 15. Other bearing supports for this shaft may be provided at 16, if so desired. Supported from the standards are opposed vertically extending slides 17 with which coat the ends of a cross head 18. This cross head is connected with the crank 15 by a connecting rod 19. The shaft 14 may be driven in any suitable manner.

Beneath the slides, a hopper 20 is supported from the standards. This hopper is in the form of an open-bottomed receptacle having downwardly sloping sides and has extended therethrough a feed tube unit, generally designated at 21. This feed tube unit consists of an annular series of vertically extending tubes 22 surrounded intermediate their ends by a band 23 secured to each thereof and to the hopper. The upper ends of the tubes are secured to a ring 24, so that the rings are held in fixed position with relation to one another and the hopper. Mounted for oscillation upon the ring 24 is an agitator ring 25 from which depend agitator pins 26 corresponding in number and arrangement to the tubes. The tubes immediately above the lower end of the hopper are each provided in their outer faces with feed openings 27 adjacent which the lower ends of the pins extend. Mounted upon the supports and having driving connection with the shaft 13, as indicated at 28, is a shaft 29 from which is driven a vertically extending shaft 30, the upper end of which mounts a disk 31 having an eccentrically disposed pin 32 connected by a link 33 with the agitator ring 25.

Slidably surrounding the tube assembly is a feed control gate 34 which is movable vertically upon the feed tube assembly from a point where it covers the feed openings 27 to a point where these openings are fully exposed and placed in communication with the hopper. The spaces between adjacent feed tubes between the lower end of the feed gate when in the last named position and the lower end of the hopper are blocked to prevent passage

of material therebetween, as indicated at 35. Secured to the outer face of the feed gate at diametrically opposed points are pins 36, with which engage the forked ends 37 of arms 38 secured to a rock shaft 39. This shaft 39 has a third arm 40 to which is secured a vertically extending push rod 41 coacting with a quick-action cam 42 mounted upon a shaft 43 supported from a pair of standards. This shaft 43 has secured thereto a gear 44 retained by a pawl 45 against rotation in one direction and having meshing therewith a gear 46. An oscillating arm 47 associated with this gear and extending into the path of the cross head 18 or some other vertically reciprocating part actuated from the crank shaft is provided with a ratchet 48 for advancing the same, so that at each reciprocation, the shaft 43 is advanced in its rotation. 20 After a predetermined number of reciprocations, the cam 42 engaging the push rod 41 rocks the shaft 39, elevating the gate and exposing the feed openings. This occurs as the cross head is moving upwardly. The cross head 18 has secured thereto a foot 49 which engages one of the arms 38 as the cross head moves downwardly upon its next stroke to force the gate downwardly and again close the feed openings. 30 Secured to the cross head 18 is a supporting plate 50 having secured thereto the upper ends of vertically extending plungers 51 corresponding in number and arrangement to the feed tubes 22 and extending thereinto. 35 Each plunger 51 at its upper end 52 is made as a substantial fit in the feed tube but slides freely therein. From a point adjacent its upper end and which, always in the reciprocation of the plungers, lies above the opening to its lower end, it is reduced in size, as indicated at 53, so that ample clearance is provided between the walls of the tube and the plunger. The lower end of the plunger is formed with a foot 54 which, when the plunger 40 is in its lowermost position, extends below the lower end of the tube. That portion of the lower end of the tube in which this foot operates is slightly increased in size, as indicated at 55, so that the clearance provided between the plunger and the wall of the tube 45 is maintained. 50 In the base and in axial alignment with the tube assembly 21 is a pilot tube 56 within which is vertically slidably mounted a tension drum 57. This drum has coacting therewith a compression brake 58 controllable through a lever 59 which may be set to secure a desired tension of the brake upon the drum by a segment 60 with which a latch 60 carried by the lever coacts. The upper end of the tension drum has secured thereto a ring 61 upon which is seated the lower end of a sheet metal form 62 adapted to interiorly fit the jacket 63, the pockets 64 of which are 55 to be stuffed. A windlass structure 65 is

mounted upon the standards and is connectible with the drum at 66 to elevate the same.

The particular construction above described is intended for use in stuffing the pockets of a jacket such as illustrated in my prior patent above identified. In use thereof, the jacket is slipped over the form 62 and then elevated until the lower ends of the plungers, when in their lowermost position, are disposed at a point adjacent the lower ends of the pockets. The drum 57 is then secured by the brake 56 which is set at the desired tension. The shaft 14 is then set in motion. The feeding is carried out in the manner previously described and the reciprocation of the plungers forces the cork end therethrough into the bottoms of the pockets and packs the same thereagainst. When this cork has been compressed to a predetermined degree, the resistance to movement of the plungers exceeds the resistance of the drum 57 to movement, with the result that the drum 57 will be forced downwardly through the brake, providing space in the pockets 64 for the reception of fresh cork to be packed by the 90 plungers. In this manner, the state of compression of cork in the pockets may be very readily determined. It has been discovered by practical tests that with a construction such as illustrated and described, packing of the cork either about the plungers or in the hopper is avoided. This is an important feature of the invention since cork is a material extremely difficult to handle, due to its tendency to pack. The loose fit of the plungers 95 provides a space through which the cork may move downwardly without interference and this same space provides a storage room for cork which, due to lack of space, cannot pass from the lower end of the tube into the 100 pocket 64 in which the plunger is operating. 105

It will be obvious that the construction hereinbefore set forth is capable of a certain range of change and modification.

I claim:—

1. In apparatus for stuffing receptacles with yieldable substances in a predetermined state of compression, tubular feeding means for the substance, a plurality of plungers slidably mounted in said feeding means for compressing the substance in the receptacle, a support for the receptacle mounted to move in the direction of movement of the plunger and adjustable friction means resisting movement of the support. 115

2. In apparatus for stuffing receptacles with yieldable substances in a predetermined state of compression, tubular feeding means for the substance, a plurality of plungers slidably mounted in said feeding means for compressing substance in the receptacle, a support for the receptacle yieldable in the direction of movement of the plunger, and an adjustable friction brake engaging the support to resist movement thereof. 130

3. In apparatus for stuffing receptacles with cork and the like, a tube adapted to extend into the receptacle and substantially fit the same, a plunger having a fit in the tube providing a space therebetween through which the substance may pass and means for feeding the substance through the side wall of the tube.

4. In apparatus for stuffing receptacles with cork and the like, a tube adapted to extend into the receptacle and substantially fit the same, a plunger having a fit in the tube providing a space therebetween through which the substance may pass, means for feeding the substance through the side wall of the tube and a support for the receptacle yieldable longitudinally of the plunger upon the application of a predetermined pressure thereto.

5. In apparatus for stuffing receptacles with cork and the like, a tube adapted to extend into the receptacle and substantially fit the same, a plunger having a fit in the tube providing a space therebetween through which the substance may pass, means for feeding the substance through the side wall of the tube, a support for the receptacle mounted to shift longitudinally of the plunger and adjustable friction means resisting movement of the support.

6. In apparatus for stuffing receptacles with yieldable substances in a predetermined state of compression, a support for the receptacle, means for feeding the substance to the receptacle, a reciprocatable plunger for packing the substance in the receptacle and means permitting separation of the support and plunger and resisting such separation until the material is packed in the receptacle to a predetermined extent.

7. In apparatus for packing receptacles with yieldable substances, a hopper adapted to receive the substance, a support adapted to receive the receptacle, a tube extending from the hopper into the receptacle and arranged upon the support, a reciprocatable plunger operating within the tube and spaced from the walls thereof, the tube within the hopper having an opening, a gate controlling the opening, means for reciprocating the plunger and means operated by reciprocation of the plunger for periodically opening and closing said gate.

8. In apparatus for packing receptacles with yieldable substances, a hopper adapted to receive the substance, a support adapted to receive the receptacle, a tube extending from the hopper into the receptacle and arranged upon the support, a reciprocatable plunger operating within the tube and spaced from the walls thereof, the tube within the hopper having an opening, a gate controlling the opening, means for reciprocating the plunger, means operated by reciprocation of the plunger for periodically opening and closing

said gate, and an agitator operating within the hopper adjacent the opening of the tube.

9. In apparatus for packing receptacles with yieldable substances, a hopper adapted to receive the substance, a support adapted to receive the receptacle, a tube extending from the hopper into the receptacle and arranged upon the support, a reciprocatable plunger operating within the tube and spaced from the walls thereof, the tube within the hopper having an opening, a gate controlling the opening, means for reciprocating the plunger, means operated by reciprocation of the plunger for periodically opening and closing said gate, a support for the receptacle movable in the direction of movement of the plunger and means frictionally resisting movement of the support.

10. In apparatus for packing receptacles with yieldable substances, a hopper adapted to receive the substance, a support adapted to receive the receptacle, a tube extending from the hopper into the receptacle and arranged upon the support, a reciprocatable plunger operating within the tube and spaced from the walls thereof, the tube within the hopper having an opening, a gate controlling the opening, means for reciprocating the plunger, a rotatable shaft having a cam, ratchet mechanism operated by reciprocation of the plunger for periodically advancing said shaft, a rock shaft having an arm engaging said gate and a second arm provided with a plunger coacting with said cam to open the gate, and means moving with the plunger for closing said gate.

In testimony whereof I hereunto affix my signature.
